CIRCUIT CONTROLLER

Burdette W. Foss and Walter McGee, Fort Wayne, Ind.; said Foss assignor to said McGee

Application December 11, 1939, Serial No. 308,632

4 Claims. (Cl. 200—27)

This invention relates to circuit controllers and more particularly to controllers of the type especially adapted for use in connection with traffic or other signals.

In regulating traffic at desired points along a throughfare and especially at intersecting or meeting highways, the time intervals during which the traffic is allowed to proceed along the main or preferential highway and along the cross-highway are not necessarily the same. It is customary, therefore, to vary the ratio of the "go" interval in the main highway to the "go" interval in the cross-highway. Light signals for controlling traffic are now in general use in which a red signal usually indicates "stop" and a green signal indicates "go"; and an amber signal is frequently used to indicate a change from "go" to "stop" or from "stop" to "go." It is also desirable, in order to expedite the movement of traffic on some highways, to control the traffic signals at two or more successive cross-highways as a group and it may be desirable at some intersections to provide signals for pedestrian traffic and for three or more thoroughfares that meet at a common point.

It is an object of our invention to provide a traffic signal with signals for two or more highways that intersect or meet at a given point and to provide a novel controlling mechanism by means of which the cycle of operation of the signal may be regulated in accordance with the demands of traffic at such point or groups of points.

The objects of the invention are accomplished by the means hereinafter described and illustrated in the accompanying drawings in which—

Figure 1 is a side elevation of a controller unit partly in section and attached to a mounting plate.

Fig. 2 is an end elevation of the unit.

Fig. 3 is a longitudinal cross-section of the unit removed from the supporting bracket and plate.

Fig. 4 as an elevation of one end of the unit shown in Fig. 3.

Fig. 5 is an elevation of the opposite end of said unit.

Fig. 6 is a cross-section on line 6—6 of Fig. 3.

Fig. 7 is an elevation of the breaker arm shown in Fig. 6.

Fig. 8 is a cross-section on line 8—8 of Fig. 3.

Fig. 9 is an elevation of the breaker arm shown in Fig. 8.

Fig. 10 is a side elevation partly in section of modified form of the controller unit.

Fig. 11 is a longitudinal cross-section of the latter modification.

Fig. 12 is a cross-section on line C—C of Fig. 11.

Fig. 13 is a cross-section on line D—D of Fig. 11.

Fig. 14 is a cross-section on line E—E of Fig. 11.

Fig. 15 is a cross-section on line F—F of Fig. 11.

Fig. 16 is a schematic representation of a timer having the unit shown in Fig. 10, the case being in section.

Fig. 17 is a front view of the same unit.

Fig. 18 is a schematic representation of the circuit connections between the latter timer and a signal.

Referring to the illustrative drawings, and particularly to Figs. 1 to 9, the controller for a single circuit comprises two cams 1, 2 (Fig. 3) that are fixed on the cam sleeves or shafts 3, 4 respectively. The cam sleeves are revolubly mounted on the shaft 5, sleeve 4 being suitably secured to the revoluble shaft 5 as by the pin 6. A spacer sleeve 7 on the shaft 5 retains the cams 1, 2 in proper position. Cam 1 is rotated by rotating the shaft 5 which drives the sleeve 4. The cams and the spacer sleeve 7 preferably are formed of suitable insulating material. Two ball or roller bearings (any suitable bearing) 8, 9 support the rings 10, 11 on the sleeves. The rings 10, 11 are formed of insulating material and are connected together by the posts 12, each post having a spacing sleeve 12' between the rings and formed of insulating material. A hub 13 carrying a gear 14 is attached to the outer face of the ring 11. Suitable means is connected to the gear 14 to drive the rings at a predetermined speed.

A slip ring 15 is fixed on the periphery of the ring 11 and a similar slip ring 16 is similarly fixed on the ring 10. A spindle 17 and a lug 18 project from the inner face of the ring 11. A breaker arm 19 is loosely mounted at one end on the spindle 17 and a flat spring 20 is fixed to the breaker arm, the opposite or free end of the spring being attached by the screw 21 to the lug 18. This spring holds the breaker arm 19 on the cam 2. A breaker point 22 is fixed on the breaker arm adjacent to its free end. The free end of the spring 20 is electrically connected by the jumper 23 to the slip ring 15, so that the breaker point 22 is electrically connected by the breaker arm 19, the spring 20 and the jumper 23 to the slip ring 15. A similar breaker arm 24 having a breaker point 25 thereon is similarly

mounted on the ring 10 and contacts the cam 1 and it is electrically connected by the similar spring 26 and jumper to the slip ring 16. The two breaker arms are of proper shape so that their breaker points are adapted to abut one another.

The assembly shown in Fig. 3 is mounted in the bracket 27, Fig. 1, and suitably held therein as by the slotted plate 28 secured to the bracket and engaged in a groove 29 formed in the projecting end of the cam sleeve 4, the outer ends of the cam sleeves and of the shaft 5 being projected through the opposite ends of the bracket. Two brushes 30, 31 are supported in insulating bushings 32, 33 respectively that are mounted in the bracket 27. The brush 30 is held in contact with the adjacent slip ring 15 by a spring 34, and it is connected to a bar 35 mounted on the top of the bushing 22 by a shunt wire 36. The brush 31 is similarly engaged on the slip ring 16 and connected to the bar 37 on the other bushing 33.

The bracket 27 may be secured to a plate 33 with the sleeve 3 and the shaft 5 extending through an opening 39 in said plate, which plate may be designed to support any number of the units. A dial plate 40, centered on the cam sleeve 3 and held in position by the screw 41, carries a fixed annularly slotted or apertured member 42 and two pointers 43, 44, cooperate with said dial. The pointer 43 is secured to the cam sleeve 3 and the pointer 44 is secured to the shaft 5. By swinging the pointers in proper direction on the dial the cam sleeves 3, 4 are turned to adjust the relative positions of the two cams 1, 2. The circuit wires 45, 46 lead from the bars 35, 37, respectively to the signal that is to be controlled.

The rotor, consisting of the gear-carrying hub 13, the inter-connected rings 10, 11, the springs and the breaker arms, is rotated at a selected constant speed preferably by an electric motor M (Fig. 11) which is connected by suitable gearing to the gear 14 on the hub 13.

The unit thus far described controls a single circuit. The cams 1, 2 are adjusted by swinging the pointers on the dial to the proper points in accordance with the determined interval of time the signal shall operate during a complete revolution of the rotor. During such revolution the breaker arms, as they ride on the respectively adjacent cams, drop down over the ledges 1', 2' on said cams in succession according to the relative peripheral spacing of said ledges, and close and separate the breaker points alternately at the determined intervals, thereby closing and opening the circuit to the signal at predetermined intervals during each revolution of the rotating unit.

Any number of the units may be grouped to control a signal.

A modified form of the unit is illustrated in Figs. 24-29, by which all signal indications are controlled. This unit has four cams, 100, 101, 102 and 103 which are fixed respectively to the cam shafts 104, 105, 106 and 107. These cam shafts fit loosely over each other so that they may be manually rotated by the pointers 108, 109, 110 and 111 that are attached to them respectively. The pointer 109 is attached to the shaft 115 and may be connected to the cam shaft 107 by tightening the set screw 116. Spacers 112, 113 and 114 hold the cams in proper relation to each other. A ring 117 of insulating material is adjacent to the cam 103, three similar rings 118, 119, 120 are positioned between the cams 101 and 102 and a similar ring 121 is adjacent to

the cam 100. All the rings are tied together by the rods 122, 122^a, 122^b, having insulating sleeves 123 thereon. A gear 124 is fixed to the plate 125 formed of insulating material that is secured to the ring 121, as by the screws 126 which extend into the rods 122. Slip rings 127, 128, 129, 130 and 131 are attached respectively to the peripheries of the rings 117, 118, 119, 120, 121.

A breaker arm 132 (Fig. 29) fits loosely on the hollow shaft 133 that projects from the inner face of the ring 121. A spring 134 is fixed at one end to the breaker arm 132 and its opposite end is secured to a stud 135 that projects from a plate 136 which is in electrical contact with the rod 122^a. This arm rides on the cam 100. The breaker arm 132 carries a breaker point 137, and an arm 138, carrying a breaker point 139, is attached to the arm 132 with insulation 140 between them and an insulating plate 141 on the outer face of the arm 138. A wire 142 is connected to the arm 138 and to a plate 143 that is in electrical contact with the rod 122. Thus the breaker point 137 is electrically connected to the rod 122^a and the point 139 is electrically connected to the rod 122. The breaker arm 144 (Fig. 28) rides on the cam 101 and is similar in form to the breaker arm 65 (Fig. 19) and similarly mounted on the ring 120. The spring 145 is secured to the arm 144 and to a stud 146 on the ring 120 and a jumper 147 is connected to the spring and to the slip ring 130. The arm 148 carrying the breaker point 149 is insulated from the arm 144, the latter carrying the breaker point 150. A wire 151 is connected to the arm 144 and to the plate 152 (Fig. 29) on the ring 121, the plate being fixed to the slip ring 131. Thus breaker point 150 is electrically connected to the slip ring 130 and the breaker point 149 is electrically connected to the slip ring 131.

A breaker arm 153 rides on the cam 102 and is mounted on the ring 112. It carries two breaker points 154, 155 similarly to the breaker arm 62 (Fig. 18) and the spring 156 is secured to the arm 153 and to the stud 157 which contacts the plate 158 mounted on the ring 112. A jumper 159 electrically connects the plate 158 to the slip ring 129.

The breaker arm 160 (Fig. 26) is similar to the breaker arm 144 and is loosely mounted on the ring 117. It rides on the cam 103. Its breaker point 161 is electrically connected to the slip ring 127 through the spring 162, the stud 163 and the jumper 164. The stud 163 also contacts the plate 165 which is in contact with the rod 122. The other breaker point 166 is connected by the arm 167, the wire 168 and the plate 169 to the rod 122^a, and a wire 170 is connected to the plate 169 and to a lug 171 that is connected to the slip ring 128.

The rotor formed by the five connected rings is mounted on the bearings 172, 173 and when in operation the breaker arms 132, 144, 153, 160 ride on the cams 100, 101, 102, 103 respectively. The breaker points 137, 139 on the arm 132 are between the breaker points 149, 150 on the arm 144 and the breaker points 154, 155 on the arm 153 are between the breaker points 165, 161 on the arm 160. When the cam 100 permits the arm 132 to drop the breaker point 137 engages the breaker point 150. When the cam 101 permits the arm 144 to drop the breaker point 149 engages the breaker point 139 and disengages the breaker points 137, 150. When the cam 102 permits the arm 153 to drop the breaker point 155 engages the breaker point 161 and when the cam 103 permits the arm 160 to drop the breaker point 160

contacts the breaker point 154 and disengages breaker points 155 and 161.

The spring opposed brushes 174, 175, 176, 177 and 178 contact the slip rings 127, 128, 129, 130, 131 and are connected respectively to plates on the insulation 184 to which the wires 179, 180, 181, 182 and 183 are connected respectively. In Fig. 32 the wire 179 connects the breaker points 139 and 161 to the north and south G signals and to the east R signal; wire 180 connects the breaker points 137 and 166 to the north and south R signals and to the east G signal; wire 181 connects the breaker points 155 and 154 to the source of current G'; wire 182 connects breaker point 150 to the east and west A signals and wire 183 connects the breaker point 149 to the north and south A signals. All the signals have a common return 192 to the source of power.

The unit is driven by the motor 184 (Fig. 30) through the gears 185, 186, 187, 188, 189 and 124. When it is desired to change the total time cycle, the gear 187 may be removed and different size of gear substituted. Gear 190 may be put in mesh with the substituted gear by releasing the thumb screw 180 and swinging the arm 191 in proper direction since the arm 191 is pivoted concentric to the gear 185 and the gear 186 is mounted on the arm. Each of the pointers 198, 199, 190, 111 carries a knob at its free end which is adapted to engage in any opening or depression 192 in the front plate upon which the unit is mounted. The duration of each signal indication is adjusted by the pointers.

What we claim is:

1. A circuit controller comprising a frame having alined bearings in its ends, a pair of sleeves each mounted in a respective bearing for rotation in said frame, cams each fixed on a respective sleeve, a shaft extending through said sleeve and having one of the sleeves fixed thereto, the other sleeve being rotatable with respect to the shaft to constitute a freely adjustable sleeve, contact arms spring held against said cams and having terminal points in opposed alinement, spaced contact rings each adjacent a respective cam and revoluble on a respective sleeve, means connecting said contact rings for simultaneous rotation of the rings, means for rotating one of said rings, brushes engaging said rings, a pair of cam setting pointers one of which is fixed to the shaft and the other to said freely adjustable sleeve, and connections between the contact points and rings.

2. A circuit controller comprising a frame having alined bearings in its ends, a pair of sleeves each mounted in a respective bearing for rotation in said frame, cams each fixed on a respective sleeve, a shaft extending through said sleeve and having one of the sleeves fixed thereto, the other sleeve being rotatable with respect to the shaft to constitute a freely adjustable sleeve, contact arms spring held against said cams and having terminal points in opposed alinement,

spaced contact rings each adjacent a respective cam and revoluble on a respective sleeve, means connecting said contact rings for simultaneous rotation of the rings, means for rotating one of said rings, brushes engaging said rings, a pair of cam setting pointers one of which is fixed to the shaft and the other to said freely adjustable sleeve, and connections between the contact points, one of said contact arms having points on its opposite sides facing outwardly and the other of said contact arms being forked to embrace the free end of the first arm and provided with internally facing contact points cooperating with the points on the first arm and insulated from each other, there being one contact ring for each point.

3. A circuit controller comprising a frame having alined bearings in its ends, a pair of sleeves each mounted in a respective bearing for rotation in said frame, cams each fixed on a respective sleeve, a shaft extending through said sleeve and having one of the sleeves fixed thereto, the other sleeve being rotatable with respect to the shaft to constitute a freely adjustable sleeve, contact arms spring held against said cams and having terminal points in opposed alinement, spaced contact rings each adjacent a respective cam and revoluble on a respective sleeve, means connecting said contact rings for simultaneous rotation of the rings, means for rotating one of said rings, brushes engaging said rings, a pair of cam setting pointers one of which is fixed to the shaft and the other to said freely adjustable sleeve, and connections between the contact points and rings, other sleeves nested on the freely adjustable sleeve and each carrying a cam and a setting pointer, other contact arms engaging the last mentioned cams and provided with coacting points similar to the first mentioned points, and contact rings and brushes electrically connected to said other points.

4. A circuit controller comprising a frame having alined bearings in its ends, a plurality of sleeves mounted in the bearings for rotation in the frame, some of the sleeves being superimposed upon each other, cams each fixed on a respective sleeve, a shaft extending through the sleeves and having one of the sleeves fixed thereto, the other sleeves being rotatable with respect to the shaft to constitute freely adjustable sleeves, contact arms spring held against said cams and having terminal points in opposed alinement, spaced contact rings each adjacent a respective cam and revoluble on a respective sleeve, means connecting said contact rings for simultaneous rotation of the rings, means for rotating one of said rings, brushes engaging said rings, cam setting pointers one of which is fixed to the shaft and the others to the freely adjustable sleeves and connections between the contact points and rings.
